SPARK PLUG

Vernon R. Thomas, Rockford, Ill.

Application October 22, 1949, Serial No. 123,034

2 Claims. (Cl. 123—169)

1

This invention relates to spark plugs of the type in which the center electrode is enclosed in a metallic dome defining an auxiliary ignition chamber which is apertured to permit the entry of the combustible mixture and rapid outward propagation of the flame after ignition.

One object of the present invention is to provide a spark plug of the above character having a gap which is adjustable in a novel manner from the exterior of the plug without destroying the gas tight seal between the relatively moving parts.

Another object is to seal the relatively adjustable parts by means of a baked cement while leaving the parts free for relative turning and longitudinal adjustment and without detracting from the effectiveness of the seal.

Other objects and advantages of the invention will become apparent from the following detailed description taken in connection with the accompanying drawings, in which

Figure 1 is an elevational view of a spark plug embodying the novel features of the present invention.

Fig. 2 is a section taken along the line 2—2 of Fig. 1.

Fig. 3 is a sectional view taken along the line 3—3 of Fig. 2.

While the invention is susceptible of various modifications and alternative constructions, I have shown in the drawings and will herein describe in detail the preferred embodiment. It is to be understood, however, that I do not intend to limit the invention by such disclosure but aim to cover all modifications and alternative constructions falling within the spirit and scope of the invention as expressed in the appended claims.

The improved spark plug is similar in general construction to the plugs commonly used in internal combustion engines including a cylindrical metallic shell 10 having an upper portion usually of hexagonal cross section and a lower portion of reduced diameter externally threaded at 11 to screw into an opening in the cylinder head of an engine. The center electrode comprises a round rod 12 extending through a tube 13 of hard ceramic material having an internal flange 14 seated against an internal shoulder 15 in the shell 10 and clamped against the latter by a screw plug 16.

The inner gradually tapering end portion 17 of the ceramic tube is enclosed by the threaded part of the shell 10 and by a frusto conical dome 18 integral therewith and having a plurality, four

in the present instance, of angularly spaced holes 19 of about .110 of an inch in diameter extending diagonally through the cone. The end of the dome 18 is flat and preferably formed at its center with a hole 20 about .078 of an inch in diameter. The shell 10, the dome 18, and the tapered end 17 of the tube cooperate to define an auxiliary combustion chamber 21 around the end 22 of the center electrode 12 which end 10 faces toward and is disposed parallel to the inner flat surface 23 of the dome 18 with which the electrode cooperates to define a spark gap of the desired width. A large sparking area is thus provided so as to insure proper combustion of the gas within the chamber 21 followed by rapid propagation of the resulting flame outwardly through the holes 19 and 20 in a plurality of jet-like streams. Very efficient ignition of the main mass of combustible gas in the engine cylinder is thus achieved.

Provision is made for adjusting the center electrode 12 axially by means of a tool engaging the electrode at a point exteriorly of the plug. For this purpose, the outer half portion of the rod 12 is larger than the electrode end and is threaded into an elongated nut 24 cemented tightly into a cylindrical counterbore 25 in the ceramic tube 13. A slot 26 or other tool receiving recess is formed in the outer end of the screw to enable the rod to be turned within the nut and the electrode end 22 to be advanced toward or away from the surface 23 of the grounded electrode.

The smooth inner end portion of the electrode rod 12 extends loosely through a bore 27 in the ceramic tube and, in accordance with the present invention, a thermally set seal of ordinary spark plug cement is formed between the opposed surfaces of the electrode rod and the ceramic tube preferably extending throughout the length of the bore 27 as indicated at 28 and over part of the axial length of the recess within the counterbore 25 between the inner end thereof and the end of the nut 24 as indicated at 29. The cement employed is ordinary spark plug cement which, after baking at about 150 degrees F. for several hours, becomes a hard mass having about the same heat conductivity as the ceramic of the tube 13.

Provision is made for forming the seals 28 and 29 while preventing adherence of the cement to the surface of the rod 12 so that the latter, after baking of the cement, may be turned within the seals and advanced axially by the action of the screw and nut. This is accomplished by

applying to the surface of the rod before application of the cement and extremely thin film of any material of waxy or oily character capable of penetrating into the pores of the metal of the rod 12 or adhering well to the surface thereof without being absorbed by the coating of cement so as to prevent direct and intimate contact between the cement and the metal surface during baking of the cement. A relatively light oil known to the trade as detergent oil has been found to be particularly satisfactory.

To form the cement seals 28 and 29 and also a seal 30 around the nut 24, the nut and screw are assembled and the lower projecting end portion of the rod 12 is first dipped in the oily liquid above referred to. Then a coating of spark plug cement is painted over the entire outer surface of the rod and the nut. Next, a similar coating of the cement is applied to the interior surface of the ceramic tube 13. The rod and nut assembly are then pressed into the tube to bring the parts into their final relationship. Some of the cement is thus forced out through the bore 27, but enough cement remains in the counterbore 25 to form the seal 29 and while leaving an open recess 31 between the latter seal and the end of the nut. The resulting assembly is baked for about a day at about 150 degrees F. whereby to harden the cement which then is adapted to conduct heat nearly as rapidly as the ceramic of the tube. As used in the claims, a film of lubricant contemplates that portion of oil present between the engaging surfaces of the rod 12 and the cement after dipping of the rod in the oily liquid and baking of the cement around the rod.

With the seals 28 and 29 thus formed, the rod 12 is relatively free to turn within the hardened cement bodies, and, as a result, the rod may be adjusted axially to vary the width of the spark gap. During the advance of the rod to narrow the gap, the enlarged or threaded portion of the rod moves into the recess 31 which is longer than the maximum adjustment required during the full service life of the spark plug. Moreover, the rod 12 remains free for turning throughout the service life of the plug.

To increase the effectiveness of the seal in preventing the escape of gases outwardly through the tube, a gasket 32, preferably comprising a washer of soft metal such as a lead-antimony alloy, fits snugly around the screw and is compressed tightly against the outer end of the ceramic tube by means of a nut 33. A cap 34 threaded onto the outer end of the screw provides a suitable terminal for attachment of the ungrounded conductor to the plug.

I claim as my invention:

1. A spark plug comprising an elongated rigid tube of insulation having an axial cylindrical bore extending through one end portion, the remaining portion being counterbored, a nut rigid with said tube and projecting into the open end of the counterbore, an elongated metal electrode rod extending axially through said tube and having one end portion threaded into said nut to permit of adjustment of the rod axially of the tube, the other end portion of the rod having a smooth external cylindrical surface smaller than

said bore and extending from the counterbore through said bore beyond the open end of the latter, a gasket ring surrounding said electrode adjacent the open end of said counterbore, means compressing said gasket ring around said electrode and against said tube to form a seal, a hollow metallic shell surrounding said tube intermediate the ends thereof and rigidly supporting the tube, a second electrode on said shell cooperating with the rod end adjacent said bore to define a spark gap, and means providing a gas-tight seal around said rod within said bore permitting free turning of the rod and advance of the latter axially comprising a layer of thermally hardened spark plug cement closely surrounding said cylindrical rod surface and filling the annular space between the rod and the wall of said bore and extending into the inner end portion of said counterbore short of the thread on said rod, and a film of lubricant between the opposed surfaces of said rod and said cement layer over the entire engaging areas thereof preventing adherence of said surfaces together.

2. A spark plug comprising an elongated tube of insulation having an axial cylindrical bore extending through one end portion thereof, a nut rigid with the other end portion of said tube, an elongated metal electrode rod extending axially through said tube and having one end portion threaded into said nut to permit of adjustment of the rod axially of the tube, the other end portion of the rod having a smooth external cylindrical surface smaller than and projecting through said bore, a gasket ring surrounding said electrode adjacent said nut, means compressing said gasket ring around said electrode and against said other end portion of said tube to form a seal, a hollow metallic shell surrounding said tube intermediate the ends thereof and rigidly supporting the tube, a second electrode on said shell cooperating with said projecting end of said rod to define a spark gap, and means providing a gas-tight seal around said rod within said bore permitting free turning of the rod and advance of the latter axially comprising a layer of thermally hardened spark plug cement closely surrounding said cylindrical rod surface and filling the annular space between the rod and the wall of said bore, and a film of lubricant between the opposed surfaces of said rod and said cement layer over the entire engaging areas thereof preventing adherence of the surfaces together.
